(57)

CLAIM

The ornamental design for a cladding element for building, as shown and described.

DESCRIPTION

15.1 Bottom plan view of a cladding element for building

15.2 Bottom perspective view of a cladding element for building

15.3 Top perspective view of a cladding element for building

15.4 Top plan view of a cladding element for building

The black background in the design 15 is not part of the claimed design.

1 Claim, 4 Drawing Sheets
